(57) **CLAIM**

The ornamental design for portable computer with barcode reader, as shown and described.

DESCRIPTION

FIG. 1 is a perspective front view of a portable computer with barcode reader of the present invention;

FIG. 2 is a perspective rear view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The portions of the portable computer with barcode reader shown in broken lines form no part of the claimed design.
